UNITED STATES PATENT OFFICE.

LEE T. ALTON, OF BROOKLYN, NEW YORK.

DESIGN FOR A GAS-LAMP.

SPECIFICATION forming part of Design No. 35,427, dated December 10, 1901.

Application filed November 12, 1901. Serial No. 82,055. Term of patent 14 years.

To all whom it may concern:

Be it known that I, LEE T. ALTON, a citizen of the United States, and a resident of the city of New York, borough of Brooklyn, county 5 of Kings, and State of New York, have invented and produced a new and original Design for a Gas-Lamp, of which the following is a specification.

My invention resides in a new and original 10 design for a gas-lamp, and the essential features thereof are substantially as illustrated in the drawing forming part of this specification, which is a side elevation of the lamp, partly in perspective.

15 In the drawing the lamp is distinguished by a long narrow tube 1, having the lower bell-shaped part 2 and an inverted circular and conical part 3, located slightly below the top of the tube, which top has alining apertures

4 therein. The lower circular bell-shaped 20 part 2 comprises three elements—viz., the circular conical crown-piece 5, the intermediate ring 6, and the hemispherical reflector 7. At each side of the tube 1 and extending below the part 7 and above the part 3 are parallel 25 parts 8, having inwardly-extending arms 9 crossing above the tube and below the reflector and united by the fixtures 10 11.

Having described my invention, I claim—

The design for a gas-lamp, substantially as 30 herein shown and described.

Signed at the city, county, and State of New York this 4th day of October, 1901.

LEE T. ALTON.
